[57] CLAIM

The ornamental design for a miniature cardiotachometer or the like, substantially as shown and described.

DESCRIPTION

FIG. 1 is a top perspective view of the inventive cardiotachometer;

FIG. 2 is a top plan view of the cardiotachometer illustrated in FIG. 1;

FIG. 3 is a side elevation of the cardiotachometer illustrated in FIG. 1;

FIG. 4, is a rear elevation of the cardiotachometer illustrated in FIG. 1;

FIG. 5 is a front elevation of the cardiotachometer illustrated in FIG. 1;

FIG. 6 is a bottom plan view of the cardiotachometer illustrated in FIG. 1.

The side of the cardiotachometer which is not shown is identical to that which is shown.

FIG. 1

FIG. 2

FIG. 3
